(57) CLAIM

The ornamental design for a cap for cosmetic container, as shown and described.

DESCRIPTION

FIG. 1 is a perspective view of a cap for cosmetic container showing my new design;

FIG. 2 is a front view thereof;

FIG. 3 is a top plan view thereof;

FIG. 4 is a bottom plan view thereof;

FIG. 5 is a bottom perspective view thereof; and,

FIG. 6 is a cross section view taken along line 6-6 in FIG. 3.

The broken lines depict portions of the cap for cosmetic container that form no part of the claimed design.

1 Claim, 6 Drawing Sheets
